CARBONATOR

James Kantor, Chicago, Ill., assignor to The Liquid Carbonic Corporation, Chicago, Ill., a corporation of Delaware

Application May 12, 1932. Serial No. 610,817

6 Claims. (Cl. 261—19)

My invention relates to improvements in apparatus for carbonating water for beverage purposes.

My invention has for one of its objects that of constructing a compact, quietly running, readily assembled carbonator which shall be effective in its operation, which automatically operates to maintain the supply of water constant and which shall be quiet in its operation.

10 For the purpose of disclosing my invention I have illustrated one embodiment in the accompanying drawings, in which:

Fig. 1 is a front elevation of a carbonator embodying my invention;

15 Fig. 2 is a transverse sectional view thereof, and

Fig. 3 is a detail sectional view of the water pump.

In the embodiment illustrated, I provide a front 20 plate 1 which is preferably fairly heavy in construction and may be made of cast iron or the like, having on its rear face a liner 2 of tin or other metal which is resistant to the action of carbonated water. This face plate is vertically 25 mounted upon a base 3 which base may be of stamped or cast metal and it will be noted that the plate is mounted near the front end of the base, this for counter-balancing purposes which will more fully hereinafter appear. For main- 30 taining the plate in vertical position on the base, I provide angle members, the vertical arms 4 of which extend parallel with the plate and are secured thereto by bolts or screws 5. These arms extend through the top of the base 3 and the 35 horizontal arms 6 of the angle members extend beneath the base 3, being likewise bolted or otherwise secured to the base. There are two of these arms, one at each corner of the plate. The carbonator body 7, which is adapted to be attached 40 to the rear face of the plate 1, is preferably of cylindrical shape with its rear end closed and drawn from a single sheet of metal which in itself is resistant to the action of carbonated water.

45 This metal may be of any desired character having the characteristic above pointed out and I have found that the present commercial "stainless steel" is satisfactory. The forward edge of the body is provided with an annular flange 8 by 50 which it is secured to the rear face of the plate 1. In securing the flange in position I preferably interpose between the flange and the face of the plate 1 a gasket 9 and clamp the flange between this gasket 9 and a clamping ring 10, which ring 55 is secured to the plate 1 by means of bolts 11,

which extend through the plate, the gasket, and the flange or the ring.

Water is supplied through a spray nozzle 12 mounted on the plate 1 and extending therethrough, this nozzle having a supply opening 13 extending therethrough and having spray openings in the interior end thereof. This nozzle is screw threaded at its rear end into a sleeve 14, in turn screw threaded as at 15 onto a nipple 16, likewise surrounding the nozzle 12 and extending through the plate 1, this nipple having a flange 17 on its inner end and a clamping nut 18 screw threaded on the exterior of the plate 1. The water supply nozzle is connected by a suitable connection 19 with a pump 20.

For supporting the pump 20 and its associated parts, I provide a plate 21 horizontally disposed and having a downwardly extending vertical web 22 bolted to the front face of the plate 1, part 23 of the same bolts for securing the carbonator 7 in position being likewise adapted for securing the web 22 in position. Water supply pump 20 is secured against one face of an upwardly extending bearing ear 23, which is preferably cast integral with the platform 21. A second bearing 24 spaced apart from the ear 23 extends upwardly from the platform 21 and a reciprocating yoke 25 is mounted between these bearings. This yoke is provided with supporting rods 26 and 27 supported in bearings in the ears 24 and 23 respectively and the rod 27 forms a plunger for the water pump 20. The yoke 25 is hollow and has arranged therein a sliding block 28 which in turn is mounted upon a crank pin 29 extending from a disc 30. This disc is mounted upon one end of a shaft 31 supported in ball bearings carried in bearing ears 32 and 33 extending vertically from the platform 21. Keyed on this shaft 31 and between the bearings is a spiral gear 34 meshing with a worm gear 35 on the shaft 36 of an electric motor 37. A suitable housing 38 surrounds the worm gear drive, which housing may contain the proper lubricant so that, the drive may operate in a bath of oil. By the above construction a reduction drive is provided between the motor and the pump plunger 27 and the rotary movement of this drive is converted into a reciprocating movement by means of the scotch yoke heretofore described.

CO₂ is admitted to the carbonator at the bottom 105 thereof through a supply pipe 39 connected with a suitable supply. It will be noted that this supply pipe enters at the bottom of the carbonator so that the CO₂ will pass through the body of the liquid at the bottom working up through the 110

liquid whereby a thorough mixing of the liquid with the carbonic acid gas is accomplished. A takeoff bypass 40 connects the supply pipe 39 with the pipe 15 whereby a certain proportion of the CO₂ passes into the carbonator at the top thereof and comes in contact with the water spray delivered from the spray nozzle. This CO₂ supply pipe 39 surrounds a water takeoff pipe 41 which it will be noted projects into the carbonator, at the bottom thereof, and beyond the CO₂ supply pipe.

The takeoff pipe 41 is controlled by a valve 42 and is connected with the bottle filling machines or other suitable device.

15 For controlling the level of the water in the carbonator tank 7, I provide automatic means for shutting off the water pump when the level in the tank reaches a predetermined point. To this end I provide a balancing bucket 43 supported by a connecting link 44 from a balancing lever 45, pivoted at 46 on the web 22 and having at its opposite end a counterbalancing weight 47. This lever 45 is connected by a suitable adjustable connection 48 with the switch for controlling 20 the circuit through the electric motor 37. The balancing bucket 43 receives liquid from the carbonator 7 through a takeoff connection 49 with the takeoff pipe 41 and through a flexible hose 50 which extends to the bottom of the balancing bucket. It will be noted that by this arrangement the liquid level in the balancing bucket corresponds to the liquid level in the carbonator. The top of the balancing bucket is connected by a flexible hose 51 with a connection 52 extending 25 to the pipe 14 so that the pressure in the balancing bucket 43 will always equal the pressure in the carbonator. By this arrangement as the liquid in the carbonator rises the liquid in the balancing bucket 43 rises until the weight of the liquid in the balancing bucket 43 overcomes the counter-balancing weight 47 whereby the bucket 40 will drop pulling with it the end of the lever 45 and operating the switch to cut off the motor.

In order to agitate the liquid in the carbonator body during the induction of CO₂ to the body, I provide an agitator in the form of a pair of paddles 53 mounted on a rotating shaft 54. This shaft extends through the plate 1 and through a stuffing box 55 to prevent leakage. The outer 45 end of the shaft is provided with a sprocket 56 which is connected by a drive chain 57 with a sprocket 58 on the shaft 31 whereby the agitator is driven from the motor 37.

The pump for delivering water to the carbonator is an extremely simple construction and includes the cylindrical barrel 59 having in one end thereof a flapper valve 60, in the intake connection 61. The plunger 27 operates through a stuffing box 63 at the opposite end, the entire structure being mounted on the upright ear 23.

I claim the following:

1. In a carbonator, the combination with a base, of a front plate vertically supported on said base, a carbonator body secured to the rear face of said front plate with the plate forming a cover member for the carbonator body, a gas inlet conduit supported by and extending through said front plate at the top thereof, a water inlet conduit surrounded by said gas conduit and extending through said front plate, a gas inlet conduit supported by and extending through said front plate at the bottom thereof, a water outlet conduit extending through said front plate and surrounded by said bottom gas inlet conduit, and a connection extending 65 between said gas inlet conduits.

2. In a carbonator, the combination with a base, of a front plate vertically secured on said base, a carbonator body secured to the rear face of said plate with the plate forming the cover member of the carbonator, a water inlet conduit supported by and extending through the top of said front plate, a water outlet conduit extending through and supported by said front plate at the bottom thereof, a gas conduit surrounding said water outlet conduit and extending through said front plate and a pump supported by said front plate and connected to said water inlet conduit.

3. In a carbonator, the combination with a base, of a front plate vertically supported thereby, a carbonator body secured to the rear face of said front plate with the front plate forming the cover member therefor, a water inlet conduit mounted on the front of said front plate and extending therethrough at the top thereof, a water outlet conduit mounted on said front plate and extending therethrough at the bottom thereof, a gas inlet conduit surrounding said water outlet conduit and extending through said front plate, a supporting platform mounted on said front plate at the top thereof, a water pump mounted on said platform and connected with said water inlet conduit and an electric motor mounted on said platform and connected with said pump.

4. In a carbonator, the combination with a base, of a front plate vertically mounted thereon, a carbonator body mounted on the rear face of said front plate with the front plate forming the cover member therefor, a water inlet mounted on said front plate and extending therethrough at the top thereof, a gas inlet surrounding said water inlet and extending through said front plate, a water outlet mounted on and extending through said front plate at the bottom thereof, a platform supported by and above said front plate, a pump mounted on said platform, a drive for said pump including an electric motor mounted on said platform, a supporting arm extending rearwardly from said plate and at right angles to said front plate, a lever mounted on said arm and connected with a controlling means for said electric motor, a balancing bucket arranged at one side of the carbonator and to the rear of said plate and connected to one end of said arm, a connection extending between the bottom of said balancing bucket and said water outlet conduit and a second connection extending between the top of said balancing bucket and said gas inlet conduit.

5. In a carbonator, the combination with a base, of a front plate vertically mounted on said base, a carbonator body secured to the rear face of said front plate with the front plate forming a closure member therefor, a water inlet mounted on and extending through said front plate at the top thereof, a water outlet mounted on and extending through said front plate at the bottom thereof, a supporting platform mounted on and above said front plate, a water pump mounted on said platform having a reciprocating plunger, a scotch yoke connected to the reciprocating plunger of said water pump, a slide block mounted in said scotch yoke, a rotary member mounted on said platform having a crank pin connected to said slide block, a reduction gear mounted on said platform for driving said rotary member and an electric motor mounted on said platform for operating said reduction gear.

6. In a carbonator, the combination with a base, of a front plate vertically mounted on said base, a carbonator mounted on the rear face of said base with the front plate forming a cover member

therefor, a water inlet mounted on said front plate and extending therethrough at the top thereof, a water outlet mounted on said front plate and extending therethrough at the bottom thereof, a 5 gas inlet mounted on the front plate and extending therethrough, an agitator arranged within said carbonator, a shaft for supporting and driving said agitator extending through said front plate to the front thereof, a platform supported 10 on and above the top of said front plate, a water pump connected with said water inlet and mount-

ed on said platform, said pump having a reciprocating plunger, a scotch yoke connected with the reciprocating plunger of said pump, a block mounted in said yoke, a shaft extending at right angles to said yoke, a crank pin mounted on said shaft and connected to said block, a driving connection between said shaft and said agitator shaft, an electric motor mounted on said platform and a reduction gear drive between said electric motor and first mentioned shaft.
